Patented Sept. 6, 1921.

UNITED STATES PATENT OFFICE.

FRANK KUSTERLE, OF KENOSHA, WISCONSIN, ASSIGNOR TO SIMMONS COMPANY, OF KENOSHA, WISCONSIN, A CORPORATION OF DELAWARE.

CORNER-FASTENING.

1,389,950.

Specification of Letters Patent.

Patented Sept. 6, 1921.

Application filed March 26, 1920. Serial No. 369,052.

To all whom it may concern:

Be it known that I, FRANK KUSTERLE, a citizen of the United States, residing at Kenosha, in the county of Kenosha and State of Wisconsin, have invented certain new and useful Improvements in a Corner-Fastening, of which the following is a specification.

My invention has reference more particularly to a lock or fastening device, which is adapted to be used in furniture construction for detachably connecting the end of a frame member to the side of another member, as for example, in bed construction, wherein an angle iron side rail of the bed is connected to the post of a bed-end.

The principal objects of my invention are to provide improved means for detachably securing the end of the longitudinal member of angular cross section, such as an angle iron, in a socket; to enable said member to be readily secured in a socket in reversed positions; to enable such reversed connection to be made without removing or reversing the locking device; to provide a locking member which rocks or fulcrums against a wall of the socket and applies pressure to both flanges of an angle iron in the socket, to clamp same cornerwise therein; to provide a device of this character in which the locking member remains assembled in the socket when released; and in general, to provide improved locking means of this character which is simple and inexpensive, and which may be conveniently operated and securely clamp the end of an angle iron or similar member in a socket.

On the drawings, Figure 1 is a side view of a fragmentary portion of a post and an angle iron connected therewith in accordance with my invention, said angle iron being shown in transverse section; Fig. 2, a sectional view on the line 2—2 of Fig. 1; and Fig. 3, a perspective view of the locking member which I employ for clamping the end of the angle iron in the socket.

Referring to the drawings, the reference numeral 1 indicates a fragmentary portion of a post such as the post of a bed-end, and 2, a fragmentary portion of an angle iron, such as the angle iron side rail of a bed, which is detachably connected to the post 1. For the purpose of affording such connection, the post 1 is provided with a bracket or socket member on the side thereof, which

may be of any suitable form or construction and secured to the post in any desired manner. The illustrated socket comprises a plate bent in inverted U-shape, with a top wall 3 having a depending leg 4 at each side thereof and at right angles thereto, so as to form square corners in the socket and this inverted U-shaped plate is secured edgewise against the side of a post, preferably with the face-plate 5 interposed therebetween. For securing the U-shaped member to the post and affording a bottom wall for the socket opening 6, in which the end of the angle iron 2 is inserted, a plate is bent with an intermediate loop 7, which is inserted through matching apertures 8 and 9 in the face-plate 5, and wall of the post respectively, and has a pin 10 inserted through the loop at the inside of the post with a reinforcing plate 11 preferably interposed between the pin 10 and the wall of the post.

The two side portions 12 of the looped plate at the exterior of the post are enlarged and spread apart so as to engage against the inside of the depending legs 4 of the U-shaped socket plate, and each of said side portions 12 is secured to its respective leg 4, by means of a rivet 13 or any other suitable manner.

The upper ends of the side portions 12 are bent inwardly as shown at 14 in Fig. 1, to form the bottom wall of the socket 6, and the reduced end of the cross rail 15 of the bed is inserted through an angular aperture in one of the legs 4 and its corresponding side portion 12 of the looped member so that the upper flange of the cross rail bears against the under sides of the inturned ends 14, and is secured to one of the inturned ends 14 as shown at 16 to afford a transverse connection of the socket parts.

A bolt 17 is inserted transversely through the socket 6 and has a locking member 18 inserted thereon, which is adapted to be forced laterally in the socket by a wing nut 19 on the projecting end of the bolt 17, which bears against a sleeve 20 on the bolt, said sleeve being extended outwardly through an aperture 21 in one of the depending legs 4, and having a rounded inner end 22, engaging against the back of the locking member 18, so as to permit the required rocking movement of said locking member.

This locking member 18 comprises a substantially rectangular back 23, the vertical

dimension of which is a little less than the vertical dimension of the socket 6, and is provided with a vertically elongated bolt aperture 24, permitting a slight vertical adjustment of the locking member in the socket. A pair of legs 25 extend laterally from the front face of the plate 23, one being located adjacent each end of the plate with an inclined wedge surface 26, extending from each leg to the respective end of the plate 23.

The angle iron which is to be clamped in the socket has a slot 27 extending inwardly from the end, so as to enable the end of the angle iron to pass the bolt 17 when inserted in the socket. When the angle iron is inserted in position as shown in full lines in Fig. 1, and the wing-nut 19 turned down on the bolt 17, the locking member 18 is forced laterally and the upper inclined surface 26 strikes against the edge of the upper flange of the angle iron, and tilts the locking member to a position in which the lower leg 25 bears against the lower portion of the upright flange of the angle iron. At the same time, the lower edge of the plate 23 bears against the bottom wall of the socket 6.

Further pressure applied to the locking member by the wing-nut 19 causes the surface 26 to act as a wedge, forcing the upper flange of the angle iron upwardly and laterally, and direct pressure is applied by the leg 25, against the vertical flange of the angle iron, with the combined result that the angle iron is jammed into a corner of the socket with the horizontal and vertical flanges pressed firmly against the vertical and upper horizontal walls respectively of the socket.

To reverse the angle iron, the opposite end thereof, which has a similar slot 27 is inserted in the socket 6 with the flanges positioned as indicated by dotted lines in Fig. 1, and upon tightening the wing-nut 19, the locking member 18 assumes the position shown by the dotted lines in Fig. 1 and in a similar manner clamps the angle iron in the lower left hand corner of the socket as shown in Fig. 1.

It will be observed that the locking member 18 is retained in the socket at all times, being held therein by a bolt 17 and it is unnecessary to reverse the locking member 18 to lock the angle iron in the reverse position, thus affording a convenient means for securely clamping the angle iron in the reversed positions without requiring loose parts which are liable to be displaced or lost.

While I have shown and described my invention in a certain practical form, it is to be understood that various changes and modifications may be made without departing from the principles of my invention, and I therefore do not purpose limiting the patent granted hereon, otherwise than necessitated by the prior art.

I claim as my invention:

65 1. In a device of the class described, the

combination with an angle iron having a pair of angularly related flanges, of an end fastening therefor comprising a pair of abutments, and a locking member engaging against the edge of one flange and the face 70 of the other flange for clamping both flanges against their respective abutments.

2. In a device of the class described, the combination with an angle iron having a pair of angularly related flanges, of an end 75 fastening therefor, comprising a pair of abutments adapted to receive the angle iron cornerwise therebetween, and a locking member having a wedge portion engaging the edge of one flange and a projection 80 pressing directly against the face of the other flange for clamping both flanges of the angle iron against the pair of abutments.

3. In a device of the class described, the combination with an angle iron having a 85 pair of angularly related flanges, of an end fastening therefor comprising a pair of abutments adapted to receive the angle iron cornerwise therebetween, a third abutment, and a locking member having a wedge surface at 90 one end engaging a flange of the angle iron and a bearing edge at the other end engaging the third abutment and a projection intermediate of the wedge surface and bearing edge engaging the other flange of the angle 95 iron to clamp the flanges thereof against their respective abutments.

4. In a device of the class described, the combination with an angle iron having a pair of angularly related flanges, of an end 100 fastening therefor comprising a pair of abutments adapted to receive the angle iron cornerwise therebetween, a locking member 105 having a wedge portion engaging the edge of one of the flanges of the angle iron and a bearing spaced therefrom engaging the other flange of the angle iron, and threaded adjusting means engaging the locking member intermediate of the wedge portion and bearing for operating the locking member to 110 clamp the angle iron against the pair of abutments.

5. In a corner fastening, the combination of an angle iron, a socket adapted to receive the end of the angle iron therein, and means 115 for locking the end of the angle iron in the socket comprising an integral locking member adapted to swing transversely of and on the angle iron as a fulcrum and thereby effect a binding engagement with a wall of 120 the socket and both flanges of the angle iron to clamp the latter in the socket.

6. The combination of an angle iron and a member detachably connecting with the end of the angle iron, said member having 125 a laterally extending socket admitting the end of the angle iron therein, a threaded member and a one piece locking member loosely mounted in the socket and adapted to be tilted therein by the threaded member, so 130

as to engage both flanges of the angle iron and a wall of the socket for clamping the end of the angle iron in the socket.

7. The combination with an angle iron of 5 a member detachably connecting with the end of the angle iron and having a socket adapted to receive the end of the angle iron therein, and a locking member in the socket having three bearing edges adapted to bear 10 respectively against the two flanges of the angle iron and a wall of the socket for clamping the end of the angle iron in the socket.

8. In a corner fastening, the combination 15 of a post having a socket extending laterally therefrom, an angle iron adapted to have the end thereof secured in a plurality of positions in the socket, and a locking member having four bearing points, optionally utilized three at a time to optionally clamp the 20 end of the angle iron in the socket in either of two different positions in the socket.

9. In a corner fastening the combination

of an angle iron, a socket adapted to receive the end of the angle iron therein and means 25 for optionally locking the angle iron in reversed positions comprising a member having lateral projections and opposite beveled edges arranged so that one of the projections coöperates with one of the beveled edges 30 to lock the angle iron in the socket in one position, and the other projection coöperates with the other beveled edge to lock the angle iron in the socket in the other position.

10. In a corner fastening the combination 35 of an angle iron, a socket adapted to receive the end of the angle iron therein and means for locking the end of the angle iron in the socket comprising a plate having a lateral projection at one end and a beveled edge at 40 the other end, and a threaded member for operating said means so as to force the projection against the inner face of one of the flanges of the angle iron and the beveled edge against the edge of the other flange. 45

FRANK KUSTERLE.
